UNITED STATES PATENT OFFICE

BRYAN D. PINKNEY, OF SMITHVILLE, NEW JERSEY, ASSIGNOR TO H. B. SMITH MACHINE COMPANY, OF SMITHVILLE, NEW JERSEY, A CORPORATION OF NEW JERSEY

SANDING MACHINE

Application filed June 3, 1929. Serial No. 367,921.

This invention relates to sanding machines or similar abrading mechanisms and has particular reference to the construction of a drum therefor.

5 In one generally used type of drum two sets of jaws are provided to clamp the respective ends of the abrasive paper or cloth carried by the drum, one of these sets of jaws being adjustable and tensioned to take up 10 slack in the abrasive sheet. In order to permit access to the jaws, for replacement of the sheet, a relatively wide opening in the drum wall is necessary which results in an interruption of the abrasive surface producing 15 transverse rotation marks on work being sanded.

It has also been proposed to clamp both ends of the abrasive sheet between the jaws of a single pair. Since the jaws occupied a 20 fixed position in the drum it was necessary to take up the slack by members acting on the portions of the abrasive sheet extending from the jaws to the periphery of the drum. This not only necessitated the location of the jaws 25 a substantial distance within the periphery, where they were inaccessible, but also necessitated the provision of a wide opening as otherwise the members referred to could not produce sufficient movement of the portions 30 of the sheet with which they contacted to take up the slack.

The primary object of the present invention relates to the provision of abrasive sheet clamping means which facilitate the placement of a sheet and which serve to take up slack therein without disturbing the static or running balance of the drum, the opening of the drum being very small.

Another object of the invention relates to 40 an improved means for securing to the drum a felt or similar backing for the abrasive sheet.

A further object relates to the improved construction of clamping jaws.

Other objects will become apparent from 45 the following description read in conjunction with the accompanying drawings in which:

Fig. 1 is a view, partly in section, of an end of a sanding drum;

50 Fig. 2 is a fragmentary transverse sectional view of the drum;

Fig. 3 is a view similar to Fig. 2, illustrating the abrasive sheet clamped in the clamping jaws;

Fig. 4 is a view similar to Fig. 3 illustrating the action of the slack take-up; 55

Fig. 5 is a sectional view showing details of the clamping jaws; and

Fig. 6 is an end view of the fixed clamping jaw.

The drum consists, preferably, of a plurality of separate sections 2 fitted together and secured to a shaft 4. Axially extending openings in the various assembled sections are in alignment and form a receiving opening 6 through which the ends of an abrasive sheet extend to be clamped by suitable jaws hereafter described. One side of the opening, that which carries the leading end of the abrasive sheet against the work when the drum rotates as indicated by the arrows in Figs. 2 and 3, is formed by a hardened lip 8 secured to ledges formed on the drum sections by screws 10. The end of a yielding backing of felt or similar material is clamped between the lip and a clamp 12 secured to the lip by bolts 14. After securing the backing as described it is attached to the surface of the drum with adhesive and carried into the opening 6 at the opposite edge thereof. After the adhesive dries, the backing is 80 trimmed as indicated at 18. 75

Extending longitudinally through the sections 2 and journaled therein is a shaft 20 which projects from one end of the drum and is there provided with a squared end so that it may be rotated by a suitable wrench 22. A plurality of collars 24 are carried by the shaft, each being provided with an opening receiving one end of a spiral spring 26 the other end of which engages a counterbalancing rod 28 extending through a plurality of hinges 30 journaled on shaft 20. The outer end of shaft 20 carries a ratchet 32 engageable by a pawl 34, whereby rotation of the shaft in a clockwise direction, as viewed in Fig. 2, may be prevented. The various element described in this paragraph are similar to those disclosed in the patent to Perry, Number 891,857, dated June 30, 1908, to 163

which reference may be made for details of operation.

Extending along the drum and secured to the hinges 30 is a jaw 36, which will be referred to as a fixed jaw, said jaw being of angular cross-section, and having an outwardly extending clamp 38. An adjustable jaw 40 of similar cross-section has an outwardly extending clamp 42 arranged to be moved towards and away from clamp 38, the adjacent faces of clamps 42 and 38 being serrated or grooved to securely grip the ends of the abrasive sheet. Relative movements of the jaws are obtained by reason of the fact that slots 44 are provided in jaw 40 through which extend screws 46 threaded into jaw 36. Accordingly, if jaw 40 is urged lengthwise, its clamp 42 is simultaneously carried towards or away from clamp 38 to clamp or release the ends of the abrasive sheet therefrom. In order to conveniently move jaw 40 relatively to jaw 36, the latter is provided with an upstanding end 48 in the upper edge of which is formed a slot 50 serving as a bearing for an adjusting screw 52, threaded as indicated at 54 into an upstanding end 56 of jaw 40, and provided with a suitable head 58 adapted to be readily engaged by an adjusting tool. This screw adjustment is very advantageous in that the necessary tight engagement of the jaws with the abrasive sheet is obtained without the application of violent force such as hammer blows which, though necessary to secure jaws heretofore devised, tend to destroy them.

The operation of the improved take-up device will be clear from Figs. 2 and 3. As shown in the latter figure, the abrasive sheet 60 of sand paper, or the like, is drawn about the drum the ends 62 and 64 thereof being inturned over the edges 66 and 68 respectively and clamped between the jaws. The abrasive sheet is, of course, secured while the parts are in the position shown in Fig. 2, the tensions on springs 26 having been relieved so that the jaws may be arranged as shown in that figure. After the sheet is clamped as shown in Fig. 3, shaft 20 is turned in a counterclockwise direction to tension the springs 50 and is held by pawl 34 whereupon slack is taken up with a resultant initial positioning of the jaws somewhere between the positions shown in Figs. 3 and 4.

As the drum is now put into use, the reaction of the work on the abrasive sheet will stretch it in a direction from edge 68 to edge 66 producing slack at the latter, which will be taken up by movement of the jaws in a counterclockwise direction under the influence of springs 26. It will be noted that as the jaws move during this take-up action, their free ends move in an arc as indicated in broken lines in Fig. 3 midway across a radius joining edge 68 with the axis of rotation. At the same time, they are moving directly away

from edge 66. It thus follows that, while the distance between the free ends of the jaws and edge 66 increases very greatly during a movement from the initial to the extreme position shown in Fig. 4, the distance of the free ends from edge 68 changes only very slightly. Accordingly a very large take-up occurs at the trailing end of the abrasive sheet where the slack accumulates, while substantially no take-up occurs at the leading end, the little variation occurring there due to movement of the jaws being compensated by stretching of the abrasive sheet and compression of the backing at the edge.

Inasmuch as the arrangement herein shown brings the open ends of the jaws almost to the periphery of the drum when the abrasive sheet is being secured thereon, as illustrated in Fig. 2, no large opening in the drum is required and the opening may be made little larger than the opening of the jaws when in receiving position. If a large opening is needed to facilitate replacement of the parts or for access to the interior of the drum for other purposes, lip 8 may be removed. As a result of the narrow opening the rotation marks on the work are substantially eliminated.

What I claim and desire to protect by Letters Patent is:

1. A device of the character described comprising a cylindrical drum having an opening in its periphery with edges extending substantially parallel to the axis, clamping means for the ends of a sheet surrounding the drum, said clamping means being located inwardly of the opening and opening in alignment therewith, and means yieldingly urging the clamping means through a path in which its distance from one edge remains approximately constant while its distance from the other edge varies whereby the sheet is taken up over the latter edge.

2. A device of the character described comprising a cylindrical drum having an opening in its periphery with edges extending substantially parallel to the axis, clamping means for the ends of a sheet surrounding the drum, said clamping means being pivoted on the drum and opening in alignment with the opening in the drum, and means for yieldingly urging the clamping means about its pivot, said pivot being located so that in the movement of the clamping means its distance from one edge remains approximately constant while its distance from the other edge varies whereby the sheet is taken up over the latter edge.

3. A device of the character described comprising a cylindrical drum having an opening in its periphery with edges extending substantially parallel to the axis, clamping means for the ends of a sheet surrounding the drum, said clamping means being pivoted on the drum, and means for yieldingly urging

the clamping means about its pivot, said pivot being located so that the path of movement of the clamping means is across a radius from the center of the pivot to one of said edges, 5 and so that tangents to the path of movement extend in a direction towards the other edge, whereby the sheet is taken up over the latter edge.

4. A device of the character described comprising a cylindrical drum having an opening in its periphery with edges extending substantially parallel to the axis, clamping means located inwardly of the opening, said clamping means including a fixed jaw and 15 an adjustable jaw, means for guiding the adjustable jaw for movement whereby it moves simultaneously lengthwise of and towards or from the fixed jaw, and a screw journaled in one jaw and threaded into the other for 20 moving the adjustable jaw, the axis of the screw extending in the direction of the movement of the adjustable jaw.

In testimony of which invention, I have hereunto set my hand, at Smithville, New 25 Jersey, on this 31st day of May, 1929.

BRYAN D. PINKNEY.
